UNITED STATES PATENT OFFICE

2,428,294

ADJUSTABLE BAR SIEVE FOR THRESHERS

Sydney E. Ross, Peoria, Ill., assignor to Hart-Carter Company, Peoria, Ill., a corporation of Delaware

Application March 16, 1944, Serial No. 526,739

2 Claims. (Cl. 209—394)

1

This invention has to do with the new and improved form and construction of sieve or screen of the type which is incorporated in grain handling farm machinery such as threshing machines and is more particularly directed to the finger constructions of the tiltable slats of such screens or sieves.

The slats of the present construction are each made with a top wall and a continuous wall extending from the rearward edge of the top wall, said continuously extending wall having fingers spaced and depending therefrom for the purpose of handling the grain and separating the straw therefrom under the action of a winnowing air stream supplied in the usual manner.

It is one of the main objects of the present invention to provide the slats with turned under rearward edges forming a part of the rearward downwardly depending wall for the purpose of extending between adjacent pairs of fingers to counteract bending of these fingers out of the general plane of the rearward wall and relative to the top wall; and further to provide for reinforcing the fingers throughout their lengths to counteract flexing of any portion of each of these fingers out of their normal predetermined positions.

Another object of the present invention is to provide fingers having folded tips which are relatively flat and parallel, all of said tips being disposed in the plane of the direction of the airflow of the winnowing air stream. These folded tips provide straw guards and at the same time provide relatively large openings for handling certain types of large kerneled grain. At the same time, the fingers are so shaped as to also accommodate a small kerneled grain under the same conditions of use depending upon the amount of tilting of the individual sieve slats by means of the mechanism which is connected to said slats and which is adapted to adjust the angular position thereof.

This invention also demonstrates the use of relatively short folded tips for the fingers as well as relatively long folded tips each respectively being incorporated in interchangeable screens. This provides further flexibility of grain handling and separating from straw, etc., in view of the fact that the use of the slats wherein the folded straw guards or tips of the fingers are relatively short a greater amount of baffling or tilting of the slats will be necessary to bring the larger finger spaces into play; whereas with the form having the longer straw guards or folded finger tips a lesser amount of baffling is

2

required before the maximum openings between fingers is exposed for active use during the winnowing operation.

Not only do the folded finger tips provide a very rigid straw guard, since they provide a substantial U-shaped member inherently actively resisting bending, but the fingers are also provided with suitable reinforcing edges that connect the folded finger tips with the under turned or folded edges of the rear wall that is provided for extending between adjacent pairs of fingers.

It is also to be noted that the various formations of fingers herein disclosed and described can all be made from a single, original form of slat providing a substantially flat finger depending from the rearward wall and substantially banking the inturned edges of this rear wall disposed between adjacent fingers and which substantially flat fingers may be formed into any of the finger slats disclosed and described in this specification. This reduces manufacturing costs and simplifies the construction of the fingered slats as will be readily apparent to those skilled in the art.

25 All other objects and advantages and salient features inherent in the present sieve construction will hereinafter appear in the more detailed description, having reference to the accompanying drawings illustrating certain preferred embodiments of the invention.

In the drawings:

Fig. 1 is a plan view of the screen or sieve incorporating the slats as constructed according to the principles of the present invention to illustrate one application thereof;

Fig. 2 is a longitudinal sectional view taken substantially along the line 2—2 in Fig. 1 with a portion of the middle of the screen frame broken away;

Fig. 3 is a face view from the rearward side thereof of a fragmentary portion of one of the slats with parts broken away and in section, to illustrate the initial finger forming stage of the slats;

Fig. 4 is a similar fragmentary portion of a slat with the fingers providing a relatively large range of openings under the tilting action of the slat;

50 Fig. 5 is a sectional view taken substantially along the line 5—5 in Fig. 4 to show the semi-tubular construction of each of the fingers;

Fig. 6 is another form of finger slat wherein the finger tips have been folded;

Fig. 7 is a sectional view of the rear edge por-

tion of the slat substantially as taken along the line 7—7 in Fig. 6;

Fig. 8 is another sectional view taken along the line 8—8 in Fig. 6 to further illustrate the details of construction of a slat with this type of fingers; and

Fig. 9 is another fragmentary rear face view of a slat illustrating fingers somewhat modified from those illustrated in Fig. 6.

There are various ways in which the slats may be pivotally mounted in a threshing machine screen frame, and likewise there are several ways in which the tilting of the individual slats relative to the frame may be accomplished. The slats may be relatively long and operated by tilting mechanism which may be incorporated in the frame at either one side or the other, or the slats may be divided on each side of a centrally located operating mechanism for tilting the same.

The latter is the type illustrated in Fig. 1 wherein a frame pivotally supports a plurality of aligned slats 11. The operating mechanism is contained within the center longitudinal supporting member 12 and includes a shiftable rod or bar 13 pivotally connected at 14 to the U-shaped or Z-shaped crank ends 15 of the cross wires 16 to which the slats 11 are attached. As seen in Fig. 1 a shiftable arm or lever 17 is suitably pivoted at 18 to the frame and has a link 20 pivotally connected thereto and to the shiftable connecting bar 13 as at 21 and 22 respectively. Any motion of the arm or lever 17 will obviously draw the bar 13 forward or backward to rock the crosswires 16 by reason of the connected cranks 15 and the pivotal connections at 14 to the shiftable bar 13. Rocking of the wires 16 about their pivotal points in the frame 10 will of course angularly displace each of the slats secured to the wires to cause the sieve or screen to function in the usual manner.

Referring now more particularly to Fig. 2, it will be noted that each slat 11 is provided with a top wall 23 terminating in a forwardly extending baffle portion 24 which is bent under and reversed as at 25 to be suitably secured to the wires 16 as at 26 in any desirable manner. Each slat is also provided with a downturned rear wall as at 27 from which a plurality of spaced depending fingers 28 extend in the manner illustrated in Fig. 3. The edge portions 30 between the adjacent pairs of fingers are turned under as at 30 to cooperate with the top wall forming channels which extend in aligned relation longitudinally of the slat to reinforce the fingers against flexing with respect to the top wall of the slat.

It should also be noted as best illustrated in Fig. 3 as well as in plan view in Fig. 1 that each of the slats are provided with a plurality of transverse ridges 31 with troughs 32 therebetween, the troughs 32 being aligned with the spaces between the fingers 28 and also with the turned under edge portions 30 which bridge and reinforce adjacent pairs of respective fingers.

The fingers illustrated in Fig. 4 are designated as 33 and are the same as those shown in Fig. 2 in the cross-sectional view. The fingers 33 are made by bending back the portions 34 and 35 of the blank fingers 28 in Fig. 3 substantially to the dot and dash line position indicated in the first two left-hand fingers in Fig. 3. This forms a semi-tubular finger substantially as shown in the cross-sectional view in Fig. 5 that is reinforced throughout its length against local bending along the length of the fingers while the

turned back portions 34 and 35 connect with the bridging portions 30 between adjacent fingers formed in the manner hereinbefore described by turning under the edges of the rear wall 27.

The fingers formed as shown in Fig. 4 produce relatively long, narrow fingers wherein relatively large ranges of openings are obtained for handling a variety of larger kerneled grains without sacrificing the strength of the fingers but actually producing fingers which are stronger throughout their length against flexing and which are substantially reinforced against bending relative to the top wall of the slat structure.

Referring now to Figs. 6, 7 and 8, the slat illustrated in this form is provided with fingers 40 having folded tip portions 41 which act as straw guards. These fingers are readily made from the blank showing in Fig. 3 by crimping in the portions 42 and 43 as illustrated in the center finger in Fig. 3 substantially at the points *a* and *b* as shown. This produces fingers having the tips 41 as best illustrated in Figs. 7 and 8 which are substantially of channel cross section and relatively flat with planes of these slat finger sections disposed substantially in line with the air flow of the winnowing air stream. Furthermore, as best shown in Figs. 7 and 8, the fingers 40 are formed by the crimping action with reinforcing walls 44 and 45 edging these fingers and connecting the flat folded tips 41 with the reinforcing bridging portions 30 of the rear wall 27. This readily counteracts any flexing of the finger itself or of the flat folded tips 41 and by connecting with the bridging portions between adjacent fingers, flexing of the respective fingers relative to the top wall of the slats is readily prevented.

The fingers 48 in the modified form illustrated in Fig. 9 are substantially the same as in Fig. 6 with the exception that the folded tips 50 forming the grass or straw guards are here somewhat longer for the purpose of obtaining the greater finger openings with the minimum angular displacements of each of the slats of the screen. As is obvious in Fig. 6, with the use of finger types shown in Fig. 6, a greater angularity will be required of the slats using this finger before the full open position of the screen or sieve is obtained. As to the openings 51 in Fig. 6 and 52 in Fig. 9 for handling smaller kerneled grain under different baffling conditions, both open at substantially the same angularity but a greater winnowing range is possible with openings such as 51 than with openings 52.

The foregoing description is directed to the preferred embodiments disclosed in the drawings to illustrate certain exemplary applications of the principles of the present invention. The invention is therefore not to be limited to the precise details of construction, form or combination of parts excepting insofar as shall be determined by the breadth and scope of the appended claims.

I claim:

1. In a thresher screen having a frame, winnowing slats pivotally mounted upon said frame, and means to adjust the angular positions of said slats, said slats each comprising a top wall terminating in a continuous wall depending from the rear edge thereof, said continuous wall having a plurality of fingers depending therefrom and having an inturned edge extending between each pair of adjacent fingers to provide a bridge to prevent bending of said fingers relative to said top wall, and said fingers each having folded tips disposed with their flat planes in the direction of

the winnowing air stream and with such flat planes disposed at predetermined angles with respect to the common transverse plane of the face of the fingers, said fingers each having inturned edges connected between said folded tips and said bridge portions of said continuous wall to reinforce said fingers against bending in the length thereof and to rigidly support said folded tips.

2. In a thresher screen having a frame, winnowing slats pivotally mounted upon said frame, and means to adjust the angular positions of said slats, said slats each comprising a top wall terminating in a continuous wall depending from the rear edge thereof, said continuous wall having a plurality of spaced fingers depending therefrom in the general plane of said continuous wall to allow passage of small grain therebetween, said fingers each having a portion thereof crimped to fold the edges adjacent said portion substantially upon each other to form a relatively flat straw guard along a portion of the finger lengths, said flat straw guards each being disposed substantially at right angles to the general plane of said continuous wall and in the direction of

the flow of the winnowing airstream to pass large grains through the straw guard portions of the fingers and said screen, and reinforcing channel means connecting adjacent fingers and said top wall to prevent bending of the fingers relative to said top wall, and additional reinforcing means connecting said flattened portions of the fingers and said first reinforcing channel means to counteract flexing of said fingers or said flattened portions thereof.
